Primary Examiner — Steven J Czyz*(74) Attorney, Agent, or Firm* — ScienBiziP, P.C.(57) **CLAIM**

The ornamental design for a cover, as shown and described.

DESCRIPTION

FIG. 1 is a front, right, and top perspective view of a cover, showing my new design;

FIG. 2 is a front, left, and bottom perspective view of the cover in FIG. 1;

FIG. 3 is a rear, left, and bottom perspective view of the cover in FIG. 1;

FIG. 4 is a front, right, and top perspective view of the cover of FIG. 1 in one state;

FIG. 5 is a front, right, and top perspective view of the cover of FIG. 1 in another state;

FIG. 6 is a front elevation view of FIG. 1;

FIG. 7 is a rear view of FIG. 1;

FIG. 8 is a left side elevation view of FIG. 1;

FIG. 9 is a right side elevation view of FIG. 1;

FIG. 10 is a top plan view of FIG. 1;

FIG. 11 is a bottom plan view of FIG. 1;

FIG. 12 is an enlarged view of an encircled area labeled "12" in FIG. 1; and,

FIG. 13 is an enlarged view of an encircled area labeled "13" in FIG. 1.

The broken lines shown in the drawings are included for the purpose of illustrating portions of the cover that form no part of the claimed design.

Dot-dash broken lines in FIGS. 1, 12, and 13 framing portions of the claimed design that are illustrated for enlargements form no part of the claimed design.

1 Claim, 13 Drawing Sheets(56)
